UNITED STATES PATENT OFFICE.

JAMES A. BURNS, OF PITTSBURGH, PENNSYLVANIA, ASSIGNOR TO WESTINGHOUSE ELECTRIC AND MANUFACTURING COMPANY, A CORPORATION OF PENNSYLVANIA.

MICA-BUILDING MACHINE.

1,234,866.

Specification of Letters Patent. Patented July 31, 1917.

Application filed July 17, 1912. Serial No. 710,066.

To all whom it may concern:

Be it known that I, JAMES A. BURNS, a citizen of the United States, and a resident of Pittsburgh, in the county of Allegheny and State of Pennsylvania, have invented a new and useful Improvement in Mica-Building Machines, of which the following is a specification.

My invention relates to machines that are employed in the manufacture of insulating materials from scales or laminæ of mica, and it has for its object to provide a machine whereby the manufacture may be carried on substantially uninterruptedly and with great reliability and economy.

It has heretofore been proposed to manufacture plates or boards of insulating material by dropping scales or laminæ of mica and powdered binding material into the upper end of a suitable tower, and receiving the same at the lower end of the tower upon sheets of paper supported upon heated plates, the heat from which serves to melt the binder and to thereby cause the mica scales to adhere together. The present invention is a receiving device for the mica and binding material which is located at the lower end of the tower, and it is of such character as to permit of readily and conveniently inserting the heated receiving plates and of removing the said plates and the assembled sheets of mica.

My invention is illustrated in the accompanying drawing, Figure 1 of which is a side view of a machine constructed in accordance therewith, and Fig. 2 is an end view of the said machine.

The mica scales and powdered binding material are distributed and dropped by any suitable means into the upper end of a tower 1, only the lower end of which is here shown, the said lower end being provided with a short extension 2 that closely fits the same and is movable longitudinally thereof through a short range. The top of the extension 2 is preferably provided with strips of felt which bear against the sides of the tower thereby making a close joint between the extension and the tower. The extension 2 is carried by links 3, the upper ends of which are pivoted to operating levers 4 located at or near the corners of the tower, the levers upon the same side thereof being mounted upon, and rigidly secured to, shafts 5, and the levers upon opposite sides of the

tower being connected by means of links or rods 7, the said means being provided to cause all of the levers to move simultaneously and correspondingly and to thereby raise and lower the extension 2 uniformly upon all sides.

Directly and centrally beneath the tower 1 is a bed or stand 10 having longitudinal tracks 11 upon which a table 12 is mounted, the tracks being provided with roller bearings 13 for the table. The table 12 is provided, upon its under side, with racks 14 that mesh with pinions 15 carried by a transverse shaft 16 having hand-wheels 17 at its opposite ends. The table may thus be moved longitudinally of the stand or bed by rotation of the hand wheels.

The table is adapted to receive and carry a plurality of rectangular receiving frames 18 having substantially the same internal dimensions as the tower extension 2. Each of the said frames comprises four side members that are detachably secured together at their ends by means of bolts 19, the removal of which permits of readily disassembling of the frames. The frames 18 are adapted to receive heated plates 20 upon which paper is preferably placed in order to prevent the mica from adhering thereto, and the frames are adapted to be placed successively directly beneath the tower to receive the falling mica scales and powdered binding material. When the mica and binding material are dropped in the tower, the extension 2 is, of course, lowered until it rests upon the upper end of a receiving frame 18, thereby preventing the escape of the said materials and the ingress of drafts which might interfere with the proper distribution of the materials, the tops of the receiving frames being also preferably provided with strips of felt which make tight joints between the parts. The ends of the receiving frames are provided with notches to permit of the insertion of bars 21 whereby the frames and their contents may be lifted from the table.

In the operation of the machine, a heated plate is first placed in one of the receiving frames with a sheet of paper upon it, and the said frame is then moved beneath the tower. The extension 2 is then lowered and the mica and binding material are dropped into the upper end of the tower. When a sufficient amount of the said materials has

been dropped into the tower to form a sheet or plate of the desired thickness, the tower extension 2 is raised and the receiving frame is then moved from beneath the tower while, 5 at the same time, another frame having a heated plate is moved beneath it. The tower extension 2 is then lowered upon the new frame, and, while mica and binding material are dropped into the tower, the material of 10 the sheet or plate first formed is arranged manually as may be necessary or desired, and another plate is placed therein, the heat of which assists in melting the binding material, while its weight serves to compress 15 and compact the materials beneath it. The operation continues in this manner until the frames are filled with heated plates and mica sheets, whereupon, the receiving frames are removed from the table, and disconnected at 20 their corners, leaving the plates and interposed mica in a stack until they have cooled and the binding material has set. The insulating sheets are then ready for subsequent treatment and are removed.

25 I claim as my invention:

1. A machine for manufacturing mica insulation comprising a tower, a movable ex-

tension at its lower end consisting of a rigid frame, a receiving frame, and means for effecting a sufficiently tight fit between said extension and the receiving frame to prevent the ingress of drafts into the tower, said receiving frame being mounted upon a reciprocally movable carriage for intermittently moving the receiving frame into and out of 30 alignment with the tower.

2. A machine for manufacturing mica insulation comprising a tower, a receiving frame, a reciprocally movable carriage for said receiving frame for intermittently moving it into alignment with the tower, and connecting means for effectively providing a close fitting, substantially air-tight connection between said tower and said receiving frame to prevent the ingress of drafts into 40 45 the tower.

In testimony whereof, I have hereunto subscribed my name this 5th day of July, 1912.

J. A. BURNS.
